(57) **CLAIM**

The ornamental design for a dryer vent cleaner, as shown and described.

DESCRIPTION

FIG. 1 is a front perspective view of a dryer vent cleaner, showing my new design;
FIG. 2 is an expanded view of its front;
FIG. 3 is a front view thereof;
FIG. 4 is a rear view thereof;
FIG. 5 is a right side view thereof;
FIG. 6 is a left side view thereof;
FIG. 7 is a bottom view thereof;
FIG. 8 is a top view thereof; and,
FIG. 9 is an enlarged detail view of area 9 in FIG. 8.
The broken lines in the drawings illustrate the portions of the dryer vent cleaner, which form no part of the claimed design.

1 Claim, 9 Drawing Sheets(56)
